tion of Delaware

Application December 27, 1937, Serial No. 181,781
In Great Britain January 13, 1937

14 Claims. (Cl. 139—13)

This invention relates to shedding mechanism for looms.

According to the invention, a fabric containing interlocked threads is woven by controlling a group of three warp threads consisting of an intermediate thread and two other threads lying respectively at the two sides of the intermediate thread in such a manner that during the passage of weft the intermediate thread lies in one warp sheet and the other two threads in the other warp sheet, and between one passage of weft and another transposing the two other threads so that they move to opposite sides of the intermediate thread, the transposition of the two threads being repeated at intervals during the weaving of the fabric. Because of the interchanging of the two other threads, these threads cross each other at certain picks, and the repeated crossings of threads produce an effect that can be used for patterning or other purposes.

The set of three threads controlled as above may be repeated at any desired positions in the warps. Thus, the three threads may belong to a larger group of threads operating in combination and consisting of intermediate threads and other threads forming pairs lying respectively at the two sides of each intermediate thread. For example, two groups of threads making six threads in all may lie side by side.

The thread crossings of the one group may be in phase with those of the other or out of phase. Two distinct but adjacent thread groups may be controlled so that threads in each group are transposed with other threads in that group but not with threads in the adjacent group. The transposing of the threads in each group causes the weft to be securely trapped by the transposed threads and the intermediate thread of each set of three threads, the interlocked fabric formed by the two groups comprising two distinct areas capable of division in the warp-wise direction without fraying of the divided edges.

Where the three threads belong to a group of a larger number of threads, three of the threads which are transposed may alternate with two intermediate threads, the crossing threads either operating in pairs in turn or in such a manner that one thread crosses the other two in any desired order. Again, two sets of three threads may be operated in combination, with or without an additional intermediate thread or threads. In this way, more complicated crossings of the warp threads may be effected.

The invention is of particular advantage in connection with circular looms adapted to weave tubular fabric since two adjacent but separate groups of warp threads may be woven in the interlocked manner described above to form two distinct areas capable of being cut or otherwise divided in the warp-wise direction to form two selvedges which do not fray at the divided edges.

The crossing movement of the threads may be effected by independent means engaging each thread and movable so as to transpose the relative positions of the outer threads with respect to the intermediate thread, suitable controlling means being provided to bring about the movements of the desired sequence.

Conveniently the apparatus according to the invention operates in conjunction with the existing shedding mechanism of a loom. Thus, a loom containing the apparatus according to the invention comprises means for shedding a number of warp threads after the passage of each pick of weft in a manner such that the intermediate thread of a group of three threads lies in one warp sheet and the other two threads lie in the opposing warp sheet, thread-controlling means adapted to transpose the two other threads so that they move to opposite sides of the intermediate thread, and means for operating the controlling means to transpose the two threads between one passage of weft and another.

The movements of the two outer threads of a set of three warp threads are advantageously effected by rotatable thread-controlling means. Such means, hereinafter referred to as a "twister", may in its simplest form comprise a hub or tube carrying a pair of arms substantially parallel to the hub axis. The twister is rotatably mounted with its arms extending substantially normal to the sheet of warp threads and with the free ends of its arms lying just clear of the warps when no shedding takes place.

The arms terminate in guide eyes adapted to receive a pair of threads passing through a hole in the hub axis from any suitable supply. From the guide eyes the two threads extend to the fell of the fabric, the threads leaving the guide holes substantially at right angles to the arms of the twister. With the twister so positioned that its two arms carry their respective threads to positions on each side of one thread of the sheet of warps, shedding is effected to carry that thread between the two arms, thereby permitting the insertion of a pick of weft. The intermediate thread then returns to its normal position and is shedded away from the arms for

the insertion of the following pick of weft. The twister is then rotated through half a revolution to cause the two threads controlled by the twister to change places. The intermediate thread is again shedded between the arms of the twister and a further pick of weft is inserted. The intermediate thread is again shedded away from the arms for insertion of a fourth pick of weft, and the twister is given a further half revolution to bring the two threads back to their original position, the cycle then being completed in four picks.

For some purposes, however, the twisting movements may take place less frequently, so that a greater number of picks must be inserted to complete the cycle.

While single twisters may be used independently at desired positions in the warp sheets, e. g. to produce ribs or other pattern effects, two or more twisters may also be disposed side by side or in overlapping relationship to produce more or less complicated pattern or other effects. Two twisters or two sets of twisters may also be disposed adjacent to each other without intervening warp threads so as to produce an open-work effect in the fabric.

As mentioned above, the operation of the twister brings about a locking of the warp threads and the weft threads. In addition, therefore, to producing pattern effects by reason of the crossing of the warp threads, the invention may be used primarily to secure weft threads against slipping in the fabric. For example, the invention may be used to enable the fabric to be cut warp-wise with a secure selvedge as mentioned above. Thus, if two groups of threads slightly spaced from each other are controlled in the manner above described, cutting of the weft threads may be effected between the two groups, leaving the two edges of the fabric produced secure against slipping.

The invention may therefore be used in looms adapted to weave widths of fabric intended to be cut into lesser widths. One instance of this is the weaving of tie fabrics, which are relatively narrow and yet can conveniently be woven in multi-widths on a wide loom. A further instance, as mentioned above, is in the weaving of fabrics on circular looms, in which, by reason of the continuous insertion of the weft, no selvedge in the ordinarily understood sense is provided. According to the invention, groups of warp threads can be controlled at desired positions round the loom circumference to enable the fabric to be cut either into a single piece with secure selvedges, or into two or more pieces.

Forms of apparatus according to the invention will now be described in greater detail with reference to the accompanying diagrammatic drawings of which

Fig. 1 is a part cross-sectional elevation of part of a circular loom employing rotating shuttles;

Fig. 2 is a plan of part of the apparatus shown in Fig. 1;

Fig. 3 is a front elevation of a detail of Figs. 1 and 2;

Figs. 4 and 5 are plan views of details of Fig. 3;

Fig. 6 is a part cross-sectional end elevation of a detail of Figs. 1 and 2;

Fig. 7 is a plan of a detail of Fig. 1; and

Figs. 8 to 13 are diagrams illustrating methods of forming the improved fabric according to the invention.

Referring to Fig. 1 warp threads 2 unwind

ing from beams or like supply packages (not shown) proceed downwardly in cylindrical arrangement to the fabric 5, along the fell 6 of which weft is laid by a number of rotating shuttles of which one (7) is indicated in the figure. The fabric is tubular and is supported below the fell 6 by the edge of a ring 8 outstanding from the central shaft 9 of the loom.

The warp threads 2 are shedded progressively round the loom to receive the shuttles 7 by shedding wheels 11, 12 which co-operate with a reed-like member 13 supported by a spider 14 outstanding from the central shaft 9 of the loom. The reed-like member 13 is formed with a series of radially disposed closely spaced dents 15 (of which a few are shown in Fig. 2), each of which is formed with an eye 16 at a point midway along its length and coinciding with the normal unshedded line 17 of the warp threads 2.

Alternate warp threads are threaded through the eyes 16 of the dents 15 and thus are fixed with respect to lateral movement, while the remaining threads are threaded between adjacent dents and thus are free to move radially along the spaces between the dents.

The shedding wheels 11 are carried around the loom on the inside of the warp circle by a spider 18 which is driven at shuttle speed, while the wheels 12 are carried round the loom outside the warp circle on standards 19 secured to an element (not shown) rotating at the same speed. One inner shedding wheel 11 is mounted slightly in advance of each alternate shuttle 7 (see Fig. 2) while one outer wheel 12 is mounted in similar association with each of the remaining shuttles, the disposition of each wheel being such that its periphery projects beyond the normal line 17 of the warp threads with the result that all the warp threads are pressed progressively towards and away from the loom axis respectively at succeeding shuttles.

Since, however, alternate threads 2 are fixed in the normal line 17 with respect to radial movement, only the free warp threads can move radially on being pressed, such division of the warp threads forming sheds 20 for the reception of the shuttles 7, first on one side and then on the other of the normal line 17, as indicated in Fig. 2.

In order to form an interlocked selvedge at any point round the loom to enable the tubular fabric 5 to be cut without fraying of the cut edges, pairs of alternate warp threads selected from the number which are to be employed in the selvedge are freed from the control of the reed-like member 13 and are placed under the control of a "twister" device which manipulates the threads in a manner to be described hereinafter.

The following description will be directed more particularly to the case in which fourteen adjacent warp threads are formed into a selvedge capable of being cut up the middle to form two equal widths of interlocked fabric.

Thus to manipulate fourteen warp threads a number of the dents 15 are removed from the reed-like member 13 at the desired position, and a twister 21 comprising four pairs of thread-controlling units is secured to the spider 14 near the gap formed by the removal of the dents 15.

Each thread-controlling unit of the twister 21 comprises two arms 23 (see Figs. 3, 3 and 4) formed on one end of a tubular member 24, the end of each arm being formed with a tubular guide 25. Each unit is rotatably mounted in a block 26 in a manner such that pinions 27, se-

cured to the tubes 24 form a train of engaging gears. The tubular members 24 (and hence the arms 23) are rotated by a quadrant 28 which engages one of the pinions 27 and is mounted on a spindle 29 operated at intervals by an arm 31 which is secured to the spindle and is forked at its free extremity.

Eight alternate warp threads (indicated generally at 32 in Figs. 1 and 2) are divided into 10 pairs and each pair is threaded through a tube 24 to the arms 23, each pair of threads then being divided into single threads each of which is threaded through a guide 25 and from the guide passes to the fell 6 of the fabric. The six remaining threads of the set of fourteen (indicated generally at 33 in Fig. 1) pass to the fell of the fabric through guide slots 34 formed in a plate 35 (see Figs. 1 and 7) secured to the top of the block 26 of the twister 21.

20 The twister is so positioned that the threads 32 are held near to the normal unshedded line 17 of the warp threads and are thus incapable of radial movement from such line. The remaining threads 33 controlled by the plate 35 are free to move radially between the fixed threads 32 when pressed by the shedding wheels 11, 12. Each pair of threads 32 controlled by the arms 23 of a twister unit thus co-operates with a single thread 33, making a set or group of three threads in association with each unit. The threads 33 are hereinafter referred to as the "intermediate" threads.

It will be noted from Figs. 3 and 10 that the twister 21 is so constructed that two of the units (each comprising a pair of arms 23) are disposed at a different level from the other two and are arranged so that an arm 23 of each of the upper units lies approximately midway (in the circumferential direction of the loom) between the arms 23 of the lower units, and the intermediate threads 33 are regularly disposed with respect to the arms. The reason for such disposition of the arms 23 will be apparent from the following description.

45 Secured to the spider 14 is a plate 37 provided with a vertical spindle 38 which serves as a pivot for a hollow pillar 39. A rod 40 projects outwardly from the lower end of the pillar and engages the forked end of the arm 31 secured to the spindle 29 of the twister 21. The upper end of the pillar 39 is formed with a longer rod 42 which extends outwardly from opposite sides of the pillar. In Fig. 2 the left-hand end of the rod 42 is shown broken in order to enable the rod 40 to be illustrated.

The spider 18 carries outstanding arms 10 from each of which depends a catch 43 at a position slightly in advance of each alternate shuttle, the catches being disposed in a manner such that the rod 42 is struck first at one side of the pillar 39 and then, after the passage of two shuttles, at the other side of the pillar as the spider rotates round the loom. The lowermost arm 10 illustrated in Fig. 2 is shown to be more advanced (in the direction of rotation of the spider 18—indicated by the arrow) than actually is the case. This arm is disposed slightly in advance of the shuttle following shuttle 54 (to be referred to later).

The striking of the two portions of the rod 42 in alternation causes the pillar 39 and the rod 40 to oscillate about the pivot 38 with the result that the arm 31 and quadrant 28 are also caused 75 to oscillate and thus rotate the tubular members

24 and arms 23 fixed thereto, first in one direction and then in the other.

The extent of the movement of the rod 40 is limited by stop screws 44 threaded through lugs 45 upstanding from the plate 37. The screws 44 5 are adjusted so as to limit the rotation of the arms 23 to 180° so that the arms rotate in a semi-circle, first in one direction and then in the opposite direction back to their original position.

Each catch 43 is pivoted on a stud 41 and is 10 adapted to yield against the resistance to continued motion of the rod 42 when the rod 40 strikes a stop screw 44, the catch being returned to operative position by a spring 45 after having passed the rod 42. The operation of the 15 catches 43 will be apparent from Figs. 1 and 6, the catches rotating in the direction indicated by the arrow, until they clear the rod 42.

In the intervals between its operating movements the pillar 39 is held securely with its rod 20 40 against a stop screw 44 (in order to prevent accidental rotation of the thread-controlling arms 23) by a spring locking device (see Figs. 1 and 2). The device comprises a pin 30 upstanding from the base of the pillar 39 and a ring member 46 surrounding the pillar 39 and pivotally connected to the pin. The member 46 is urged rearwardly by a spring 47 secured to a pin 48 upstanding from the plate 37. The spring 47 and ring member 46 thus co-operate to hold the pillar 39 stationary in either of its extreme positions, in a manner which will be obvious from the above figures.

At the commencement of weaving an outer shedding wheel 12 presses all the warp threads 35 inwardly towards the loom axis. The intermediate threads 33 are thus pushed along the slots 34 of the plate 35 between the threads 32 controlled by the arms 23, to the position shown in dotted line in Fig. 1 and also indicated in Fig. 10 40 and form a shed in which a pick of weft 50 is laid by a shuttle 49 (Fig. 2).

The threads 33 are thus contained in the inner sheet of warp threads while the threads 32 are contained in the outer sheet. At the next shuttle 45 (51) an inner shedding wheel 11 (shown in dotted line in Fig. 2) presses the threads outwardly, the threads 33 thus being pressed radially between the arms 23 away from the loom axis to the position shown in chain line in Fig. 1, and 50 another shed is thus formed of which the threads 32 are contained in the inner sheet and the threads 33 in the outer sheet.

Immediately before the shedding of the threads by the wheel 11 a catch 43 strikes an end 55 of the rod 42 and thus causes the thread guiding arms 23 to rotate through 180° to transpose the position of the pairs of warp threads 32 controlled thereby, as indicated in Figs. 10 and 11, the threads rotating from the positions A, B, C and 60 D to the positions A', B', C' and D'.

The transposition of the warp threads 32 causes each outer pair of threads of each set or group of three to cross behind the threads 33 disposed between them. Weft 53 is then laid in the shed 65 by the next shuttle (51). With the outer threads 32 still in their transposed position, the intermediate threads 33 are now pressed inwardly between the arms 23 by an outer shedding wheel 12 to form a shed for the reception of the succeeding shuttle (54) which lays weft 55 in the shed. After the passage of that shuttle the threads 33 are again pushed outwardly to form a further shed for the following shuttle, and a catch 43 now strikes the opposite end of the rod 70 75

42 to cause the arms 23 to rotate and transpose the threads 32 to their original positions, i. e. in which A', B', C' and D' revolve to positions A, B, C and D respectively. Weft 56 is then laid in the new shed. The threads 32 are thus crossed again behind the intermediate threads 33, this crossing completing a cycle of four picks 50, 53, 55, 56, (indicated by a bracket in Fig. 10) which is repeated in the manner described above. An 10 exceedingly firm locking of weft and warp threads is obtained by the arrangement just described.

By reason of the twisting of the threads 32 there is a tendency for a greater length of such threads to be consumed than of the intermediate threads 33 which do not have a twisting movement. For this reason, therefore, (and, if desired, to enable special threads to be used in the selvedge) the threads 32 are supplied to the twister 15 21 from a separate package 57 disposed on the spider 14 and capable of delivering threads at a different rate from that of the other warp threads. The package 57 is formed with a braking surface 20 58, the rate of rotation of the package being braked by a band and weight device 59 bearing 25 on the surface 58 in order to subject the warp threads 32 to the desired amount of tension.

It is not necessary that alternate rotations of the arms 23 should be in opposite directions. On 30 the other hand, more than one-half revolution may take place in the same direction, to be followed by a corresponding number of half revolutions in the opposite direction, by suitably modifying the quadrant and associated mechanism.

35 The downward inclination of the arms 23 (see Fig. 1) enables the end of one arm that passes above the other arm during the rotation of a pair of arms to lie at a slightly greater radial distance than the end of the lower of each pair of arms, as shown clearly in Fig. 1. The two threads 32 controlled by a single unit thus pass clear of each other as they change positions.

The selvedge woven in the manner described above is formed with two similar areas 60 (Fig. 45 10) which are separated by a dividing line 61—61 along which the selvedge may be cut without fraying of the cut edges.

A form of simple interlocking weave comprising 50 two warp threads 32 and one intermediate warp thread 33 and operating over a four-pick cycle, obtainable by using one pair only of thread-controlling arms 23, is shown in Fig. 8. Thus as a pick of weft 62 is laid, the threads 32 (indicated at E, E' in Fig. 9) lie in the outer warp 55 sheet and the intermediate thread 33 lies to the inside between the thread-controlling arms 23. When the thread 33 is pressed outwardly to form the next shed for the succeeding weft pick 63 the arms 23 are rotated through 180° (viz. E moves 60 to E' and E' moves to E) to transpose the pair of threads 32 and thus cause them to cross each other behind the intermediate thread 33.

After the laying of the weft pick 63 the intermediate thread 33 is again pressed inwardly between 65 the arms 23 so that the threads 32 again lie in the outside warp shed, and a pick 64 of weft is laid in the shed so formed. After the laying of the pick 64 the intermediate thread 33 is pressed outwardly again and the arms 23 are 70 rotated through 180° in the opposite direction back to their original positions (viz. E' moves to E and E moves to E'), such rotation crossing the threads 32 again. A pick of weft 65 is then laid in the shed, thus completing the cycle of four 75 picks indicated by the bracket in Fig. 8. The

next cycle is started as the intermediate thread 33 is pressed inwardly between the arms 23 to form a shed for the reception of a further pick 62 (i. e. the first pick of the next cycle), and the sequence of operations described above is re- 5 peated.

Another form of twisting unit according to the invention contains more than two arms 23. For example such unit may have three arms 23 controlling a corresponding number of threads 32 10 and adapted to be used with two intermediate threads 33 lying to the inside of the two outermost arms. Such three-armed unit can be given movements of say $\frac{1}{6}$ or multiples of $\frac{1}{6}$ of a revolution in any desired sequence to cause pairs 15 of threads 32 to move to opposite sides of the intermediate threads 33.

The operation of a three-armed device, and a form of weave obtainable thereby, will now be described with reference to Figs. 12 and 13. The 20 weave comprises five warp threads and operates over a sixteen-pick cycle, the twister unit being rotated through 60° in one direction at each of four alternate picks, followed by similar rotation in the reverse direction. It will be noted from Fig. 13 that the two intermediate warp threads 33 lie evenly between the three threads 32 controlled by the arms 23, the threads 32 for convenience being designated F, G, H.

Thus at the commencement of a cycle the 30 intermediate threads 33 are pressed inwardly between the arms 23 and a pick 66 of weft is laid in the shed thus formed. The threads 33 are then pressed outwardly, and after passing the extremities of the arms 23 the twisting unit 35 is rotated through $\frac{1}{6}$ of a revolution in the direction indicated by the arrow in order to cross the threads F and H, leaving thread G still to the right of the right-hand thread 33.

A pick of weft 67 is then laid in the shed and 40 the intermediate threads 33 are again pressed inwardly to form a new shed for the reception of a pick of weft 68. After the laying of the latter pick the twister unit is rotated through a further $\frac{1}{6}$ of a revolution in the same direction 45 in order to cross threads F and G, leaving thread H still to the left of the left-hand thread 33. On the next shedding motion of the threads to bring the intermediate threads 33 outwardly 50 a pick of weft 69 is laid and the threads are again shedded to reverse the positions of the threads 33 relatively to the threads F, G, H, in the manner apparent from Fig. 12.

The thread F now occupies the position in the fabric originally occupied by G, and G occupies the position originally occupied by H 55 (i. e. in the middle of the pattern), G at the next pick but one being crossed over to the position originally occupied by F, while H is brought into the middle of the pattern. At the 60 eighth pick threads F and H are transposed, while G remains to the left of the intermediate threads 33. The eighth pick represents a half of the weaving cycle which forms a completed pattern (such half-cycle being indicated by the bracket in Fig. 12), the remaining half being a reversal of the first half as will be apparent from Fig. 12.

The twisters 21 may also be used in conjunction 70 with shedding mechanism in which deflection of the normal warp threads takes place in one radial direction only, e. g. always radially inwards. Thus, the intermediate warp threads 33 may be controlled by healds or other devices under the control of the shedding mech- 75

anism so that at alternate shuttles the intermediate threads are deflected between the arms 23 of the twister 21. At the remaining shuttles the reverse shedding motion may be effected by preventing the intermediate threads from having such inward deflection and by giving the threads controlled by the twisters 21 an inward deflection, as for example by moving the twister itself radially inwardly. This movement of the twister may be controlled by means rotating with the shuttles and associated with the particular shuttles at which such movement is desired.

Having described my invention, what I desire to secure by Letters Patent is:

1. A circular loom comprising means for shedding a number of warp threads after the passage of each pick of weft in a manner such that the intermediate thread of a group of three threads lies in one warp sheet and the other two threads lie in the opposing warp sheet, thread guiding means for guiding the intermediate thread between the two other threads during shedding, rotary thread-controlling means adapted to transpose the two other threads so that they move to opposite sides of the intermediate thread, and a driving member between which and the thread-controlling means there is relative circular motion with respect to the loom axis, said driving member bringing about rotation of the thread-controlling means between one passage of weft and another to transpose the two other threads.

2. A circular loom comprising means for shedding a number of warp threads after the passage of each pick of weft in a manner such that the intermediate thread of a group of three threads lies in one warp sheet and the other two threads lie in the opposing warp sheet, thread guiding means for guiding the intermediate thread between the two other threads during shedding, a rotatable member formed with a plurality of outstanding thread guiding arms each adapted to control a thread, said arms being spaced from each other to allow of the shedding of an intermediate thread between the arms, a driving member between which and the rotatable member there is relative circular motion with respect to the loom axis, said driving member bringing about the operation of the rotatable member between one passage of weft and another to transpose the threads controlled by the arms.

3. A circular loom according to claim 2, wherein in each of the outstanding thread guiding arms is formed with a hole at its free extremity for controlling a thread, and the rotatable member is formed with a tube adapted to allow of the passage of warp threads therethrough.

4. A circular loom comprising means for shedding a number of warp threads after the passage of each pick of weft in a manner such that the intermediate thread of a group of three threads lies in one warp sheet and the other two threads lie in the opposing warp sheet, thread guiding means for guiding the intermediate thread between the two other threads during shedding, a rotatable member formed with a plurality of outstanding thread guiding arms each adapted to control a thread, said arms being spaced from each other to allow of the shedding of an intermediate thread between the arms, a tube formed in said rotatable member and adapted to allow of the passage of warp threads therethrough, a pinion formed on said rotatable member, a quadrant adapted

to drive the pinion, and a driving member between which and the rotatable member there is relative circular motion with respect to the loom axis, said driving member bringing about the operation of the quadrant to rotate the rotatable member between one passage of weft and another to transpose the threads controlled by the arms.

5. A circular loom according to claim 4 comprising an arm in association with the quadrant, the driving member bringing about rotation of the arm on said quadrant to rotate the rotatable member between one passage of weft and another to transpose the threads controlled by the arms.

6. A circular loom comprising means for shedding a number of warp threads after the passage of each pick of weft in a manner such that the intermediate thread of a group of three threads lies in one warp sheet and the other two threads lie in the opposing warp sheet, thread guiding means for guiding the intermediate thread between the two other threads during shedding, a rotatable member formed with a plurality of outstanding thread guiding arms each adapted to control a thread, said arms being spaced from each other to allow of the shedding of an intermediate thread between the arms, a pinion formed on said rotatable member, a quadrant adapted to drive the pinion, an arm in association with the quadrant, a pivoted rod in connection with the quadrant arm, a further pivoted rod in driving engagement with the first-mentioned pivoted rod, and yieldable catches secured to a member between which and the rotatable member there is relative circular motion with respect to the loom axis, said catches being adapted to strike the further rod between one passage of weft and another first on one side and then on the other of the pivot, so as to oscillate the rod and thus transmit drive to the rotatable member first in one direction and then in the other to transpose the threads controlled by the arms.

7. A circular loom according to claim 6 comprising means for regulating the extent of the movement of the pivoted rod so as to control the angle through which the rotatable member is permitted to rotate.

8. A circular loom comprising means for shedding a number of warp threads after the passage of each pick of weft in a manner such that in two adjacent groups of three threads the intermediate threads of the groups lie in one warp sheet and the other two threads of the groups lie in the opposing warp sheet, thread guiding means for guiding the intermediate thread of each group between the two other threads in the group during shedding, rotary thread-controlling means adapted to transpose the two other threads in each group so that they move to opposite sides of their respective intermediate threads, and a driving member between which and the thread-controlling means there is relative circular motion with respect to the loom axis, said driving member bringing about the operation of the thread-controlling means for each group to transpose the threads between one passage of weft and another so as to form interlocked fabric comprising two distinct areas capable of division in the warp-wise direction without fraying of the divided edges.

9. A circular loom of the type in which shedding is effected by deflecting a number of warp threads to one side of the normal line that they follow in approaching a shuttle from the warp

supply, comprising a rotatable member formed with two outstanding thread guiding arms adapted to control a pair of warp threads disposed one on each side of an intermediate warp thread and 5 out of the normal line of the warp sheet, said arms being spaced apart and disposed in such a manner as to allow free passage of the intermediate thread between the arms during shedding, means to deflect the intermediate warp 10 thread from its normal line so that it passes beyond the pair of warp threads, thread guiding means for guiding the intermediate thread between the pair of threads during shedding, a driving member between which and the rotatable 15 member there is relative circular motion with respect to the loom axis, said driving member bringing about the operation of the rotatable member between one passage of weft and another to transpose the pair of threads controlled 20 by the arms.

10. A circular loom according to claim 9 comprising a plurality of rotatable members controlling adjacent pairs of warp threads, a pinion on each of said rotatable members, said pinions being 25 connected in successive driving relation, and a gear in driving connection with one of said pinions, the driving member operating the gear between one passage of weft and another to bring about rotation of the rotatable members to transpose the threads controlled by the arms so as 30 to form interlocked fabric comprising two distinct areas capable of division in the warpwise direction without fraying of the divided edges.

11. A loom comprising means for shedding a 35 number of warp threads after the passage of each pick of weft in a manner such that the intermediate thread of a group of three threads lies in one warp sheet and the other two threads lie in the opposing warp sheet, thread guiding means 40 for guiding the intermediate thread between the two other threads during shedding, rotary thread-controlling means adapted to transpose the two other threads so that they move to opposite sides of the intermediate thread, and means for operating said controlling means to transpose the 45 two other threads between one passage of weft and another.

12. A loom comprising means for shedding a number of warp threads after the passage of each pick of weft in a manner such that the intermediate thread of a group of three threads lies in one warp sheet and the other two threads 5 lie in the opposing warp sheet, thread guiding means for guiding the intermediate thread between the two other threads during shedding, a rotatable member formed with a plurality of outstanding 10 thread guiding arms each adapted to control a thread, said arms being spaced from each other to allow of the shedding of an intermediate thread between the arms, and means for rotating the rotatable member between one passage of weft and another to transpose the threads 15 controlled by the arms.

13. A loom comprising means for shedding a number of warp threads after the passage of each pick of weft in a manner such that the intermediate thread of a group of three threads lies in 20 one warp sheet and the other two threads lie in the opposing warp sheet, thread guiding means for guiding the intermediate thread between the two other threads during shedding, a rotatable member formed with a plurality of outstanding 25 thread guiding arms, each formed with a hole at its free extremity for controlling a thread, the said arms being spaced from each other to allow of the shedding of an intermediate thread between the arms, a tube formed in said rotatable 30 member and adapted to allow of the passage of warp threads therethrough, and means for rotating the rotatable member between one passage of weft and another to transpose the threads controlled by the arms.

14. A loom according to claim 12 comprising a plurality of rotatable members controlling adjacent pairs of warp threads, a pinion on each of said rotatable members, said pinions being 40 connected in successive driving relation, and a gear in driving connection with one of said pinions, said gear operating between one passage of weft and another to rotate the rotatable members so as to transpose the threads controlled 45 by the arms.
